UNITED STATES PATENT OFFICE.

FRANK SCHILLING, OF CINCINNATI, OHIO, ASSIGNOR TO S. HIRSCH & COMPANY, OF KANSAS CITY, MISSOURI.

DESIGN FOR A BOTTLE.

SPECIFICATION forming part of Design No. 36,227, dated February 10, 1903.

Application filed August 16, 1902. Serial No. 119,976. Term of patent 7 years.

To all whom it may concern:

Be it known that I, FRANK SCHILLING, a citizen of the United States, and a resident of Cincinnati, in the county of Hamilton and State of Ohio, have invented and produced a new, original, and ornamental Design for a Bottle, of which the following is a specification, reference being had to the accompanying drawings, forming part thereof, and wherein like letters of reference indicate corresponding parts in both views.

Figure 1 is an elevation of a bottle, showing my new design thereon. Fig. 2 is a section on the line 2 2, Fig. 1.

As shown in the drawings, the leading or material features of my design consist of a bottle having the plain side portion A and the ornamental neck and shoulder portions.

The neck of the bottle is formed with a bulge B. Below this bulge are arranged a series of raised ellipses C. These ellipses are arranged in a vertical line and extend from the neck down over the shoulder, the ellipses becoming larger in size from the neck downward. These ellipses are arranged in sets of two vertical lines and entirely surround the neck and

shoulder of the bottle. Between the ellipses are arranged raised diamond-shaped portions. Between each set of ellipses are disposed vertical ribs D, extending from the neck down over the shoulder. The ribs are of the same length as the line of ellipses, and the line of ellipses and ribs have their upper and lower ends terminate, respectively, in horizontal planes. Between the ribs and ellipses are arranged a series of raised three-pointed portions E. Beneath the lower ends of the line of ellipses and ribs is arranged an annular shoulder F, upon which the series of ellipses E and ribs D terminate.

Having thus described my invention, what I claim as new, and desire to secure by Letters Patent, is—

The ornamental design for a bottle substantially as shown and described.

In testimony whereof I have signed my name to this specification in the presence of two subscribing witnesses.

FRANK SCHILLING.
